Primary Examiner — Christian P. Mclean*Assistant Examiner* — Kaitlan Walker(74) *Attorney, Agent, or Firm* — Warner Norcross + Judd LLP**CLAIM**

The ornamental design for optical sight reticle as shown and described.

DESCRIPTION

FIG. 1 is a view of the optical sight reticle embodying the new design, as viewed through an eyepiece end of an aiming device;

FIG. 2 is a view of another embodiment of the optical sight reticle, as viewed through the eyepiece end of the aiming device;

FIG. 3 is a close up view of the other embodiment of the optical sight reticle, as viewed through the eyepiece end of the aiming device; and,

FIG. 4 is a perspective view showing an environment of use for the optical sight reticle of FIGS. 1-3.

Features are shown in certain figures in broken lines. The features shown in broken lines do not form any part of the claimed design. Broken lines immediately adjacent the solid-line portions of the design form the boundary of the design, with the broken lines forming no part of the claimed design.
